UNITED STATES PATENT OFFICE.

JAMES ALEXANDER FLANAGAN, OF TORONTO, ONTARIO, CANADA.

SEWING-MACHINE.

1,887,138.

Specification of Letters Patent.

Patented Aug. 9, 1921.

Application filed February 4, 1919, Serial No. 274,902. Renewed June 1, 1921. Serial No. 474,297.

To all whom it may concern:

Be it known that I, JAMES ALEXANDER FLANAGAN, of the city of Toronto, in the county of York and Province of Ontario, 5 Dominion of Canada, have invented certain new and useful Improvements in Sewing-Machines; and I hereby declare that the following is a clear and exact description of the same.

10 This invention relates particularly to certain new and useful improvements in the feed and looper motions of a sewing machine; one of the objects of the invention being to centralize these motions, without disturbing the original action of the feed dog and looper, and thereby increase the scope of the machine and the variety of the work which it is capable of performing; a further object of the invention being to de-

15 20 25 30 35 40 45 50 55 60 65 70 75 80 85 90 95 100 105 110

15 This invention relates particularly to certain new and useful improvements in the feed and looper motions of a sewing machine; one of the objects of the invention being to centralize these motions, without disturbing the original action of the feed dog and looper, and thereby increase the scope of the machine and the variety of the work which it is capable of performing; a further object of the invention being to de-

20 25 30 35 40 45 50 55 60 65 70 75 80 85 90 95 100 105 110

25 The first of these objects may be attained by bringing the feed and looper shafts into co-axial relation and providing them with a specially designed motion for the vertical and lateral reciprocation of the feed dog; and the second of these objects may be attained by providing the feed and looper motions with a specially constructed housing to partly or wholly inclose them without disturbing the original arrangement and use of the throat-plates and the provision for the usual sewing attachments, as hereinafter set forth and particularly pointed out in the claims.

30 35 40 45 50 55 60 65 70 75 80 85 90 95 100 105 110

For an understanding of the invention reference is to be had to the following description and to the accompanying drawings, in which:—

40 Figure 1, is a horizontal longitudinal sectional plan showing the feed and looper motions;

45 Fig. 2, is a vertical longitudinal section on the line $a-a$, Fig. 1;

Fig. 3, is an elevational view of the feed dog and the feed cam imparting vertical reciprocating movement to the feed dog;

Fig. 4, is an end elevational view of the feed shaft and the rocker for imparting lateral reciprocating movement to the feed dog;

55 Fig. 5, is an end elevational view of the housing for the feed and looper motions;

Fig. 6, is a top plan view of the feed dog, part of the housing shown in Figs. 1, 2, and 5, and the throat plates; and,

Fig. 7, is a vertical section on the line $b-b$, Fig. 2.

Like characters of reference refer to like parts throughout the specification and drawings.

As an illustration of how the invention 65 may be carried into effect, I have shown in Figs. 1 and 2 the feed shaft a to be of tubular construction and journaled in suitable bearings b , b' , forming part of, or rigidly connected to, the frame; and I have also 70 shown in the same figures the looper shaft c as extending axially through the feed shaft and projecting beyond the end thereof.

This arrangement brings the feed and looper shafts into co-axial relation and permits 75 of the feed and looper motions being centralized with relation to each other and to the opening formed by the removal of the throat-plates i , i' .

On the ends of the feed shaft a are caps 80 d , d' , constituting the bearings for the looper shaft c . Fixed on the looper shaft, adjacent to the bearing d , is the feed cam e , imparting a vertical reciprocating movement to the feed dog f .

The feed dog f is provided with a feed bar f' , which rides on the peripheral surface of cam e , this feed bar being of substantially the same width as the face of the cam and, secured to the side face of the feed bar 90 is an arm f'' .

This arm f'' extends along the corresponding side face of the cam e and is provided with a foot f^3 entered in the internal cam e' formed in the side face of the cam e , 95 the contour of this internal cam corresponding with the peripheral surface of the cam e .

The cams e e' revolve with the looper shaft c and, during their revolution, impart a vertical reciprocation to the feed dog f . 100

Either the cam e or e' may be omitted if desired, but it is preferable to use the cam construction shown and described, as the peripheral cam e provides a substantial support for the feed-bar and feed dog, and the 105 internal cam e' and the arm f'' and foot f^3 provide a positive motion for the vertical reciprocation of the feed dog.

Projecting from the top of the cap d is a rocker arm d'' having a radial slot d^3 , 110 to receive the arm f'' , the dimensions of this slot corresponding with the external dimen-

sions of the arm, so that the latter will fit snugly therein.

At or near the rear end of the feed shaft *a* is the feed drive *a'*, imparting a rocking movement to the feed shaft, during which the rocker arm causes the lateral reciprocation of the feed dog by means of the arrangement of the arm *f''* and slotted rocker arm.

10 At the same end of the looper shaft *c* as the drive *a'* is the looper drive *c'*, which imparts a rotary movement to the looper shaft and causes the rotation of the cams *e*, *e'*.

15 During the operation of the drives *a'*, *c'*, the feed shaft *a* is rocked in the bearings *b*, *b'*, to cause the movement of the rocker arm and the lateral reciprocation of the feed dog concurrently with the rotation of 20 the looper shaft and the cams *e*, *e'*, which effect the vertical reciprocation of the feed dog.

In closing the feed and shuttle shafts and their related parts, which for convenience 25 may be termed the feed and looper motions, is a housing consisting of a tubular member *h* and a substantially spherical member *h'*.

The top of the spherical member *h'* is flattened and provided with a feed plate *h''* 30 suitably slotted for the feed dog *f*, and the front of the spherical member *h'* is provided with a hinged gate *h³* for access to the looper.

The purpose of the housing *h*, *h'*, is two- 35 fold, first, to inclose the feed and looper motions, and second, to provide a support for work of a tubular or like character, the latter of which is the more important, as it permits of the machine being used for darning 40 and other purposes, such, for instance, as the sewing of sleeves, trouser legs, etc., when the garment has been put together.

To permit of this use of the machine, the frame is provided with throat-plates *i*, *i'*, 45 of relatively considerable dimensions, vertically above the housing *h*, *h'*, which plates, when removed from the frame, permit of free access to the housing as a work support.

50 When these throat-plates are removed, work, such, for instance, as a sock, or a sleeve, or a trouser leg, all of tubular character, may be drawn over the spherical member *h'* of the housing and in the direction 55 of the bearing *b* until the spot where the sewing is to be done comes into alinement with the needle bar of the machine.

This centralization of the feed and looper motions and the co-axial relation of the feed 60 and looper shafts permits of a housing of this type being used and allows of the machine being employed for work of this character without interfering with its use or purpose or purposes for which it was ordinarily designed, and without interfering

with any of the attachments which it may be necessary to use in connection therewith.

Various changes in the structural details of the parts described may be made within the scope of the appended claims without departing from the principle of the invention, which is to centralize the feed and looper motions and to provide them with a housing which may be used as a support for work of a tubular character.

75

Having thus fully described my invention what I claim as new and desire to secure by Letters Patent, is:—

1. A sewing machine comprising co-axial feed and looper shafts, means for oscillating 80 the feed shaft, means for rotating the looper shaft, a cam fixed on the looper shaft, and a vertically and laterally reciprocating feed dog receiving positive upward and downward movement from the cam and lateral 85 reciprocation from the feed shaft.

2. A sewing machine comprising co-axial feed and looper shafts, means for oscillating the feed shaft, means for rotating the looper shaft, a cam fixed on the looper shaft, a vertically and laterally reciprocating feed dog 90 riding on the cam and receiving positive upward and downward movement therefrom, and an arm fixed on the feed shaft imparting lateral reciprocation to the feed dog.

95

3. A sewing machine comprising co-axial feed and looper shafts, means for oscillating the feed shaft, means for rotating the looper shaft, a reciprocating feed dog receiving lateral reciprocation from the feed shaft, a cam 100 fixed on the looper shaft, and means combined with the cam and feed dog imparting positive up and down movement to the feed dog during the rotation of the cam.

4. A sewing machine comprising co-axial 105 feed and looper shafts, means for oscillating the feed shaft, means for rotating the looper shaft, a vertically and laterally reciprocating feed dog, a cam fixed on the looper shaft, means combined with the cam and feed dog 110 imparting positive up and down movement to the feed dog during the rotation of the cam and an arm for the feed shaft imparting lateral reciprocation to the feed dog during the oscillation of the feed shaft.

115

5. A sewing machine comprising co-axial feed and looper shafts, a cam element, rotatable with the looper shaft, having a cam in one of its side faces, a feed dog riding on the peripheral surface of the cam element 120 and having a member entered in the cam to impart positive vertical reciprocation to the feed dog, and a rocker arm actuated by the feed shaft imparting lateral reciprocation to the feed dog.

125

6. A sewing machine comprising co-axial feed and looper shafts, a cam element rotatable with the looper shaft and having a cam in one of its side faces, the peripheral surface of said cam element corresponding 130

with the cam, a feed dog riding on the peripheral surface of the cam element and having a member entered in the cam for imparting a positive vertical reciprocating movement to the feed dog and a rocker arm actuated by the feed shaft, imparting positive lateral reciprocation to the feed dog.

7. A sewing machine comprising co-axial feed and looper shafts, a cam element rotatable with the looper shaft having a cam in one of its side faces, the peripheral surface of said cam element corresponding with the cam, a feed dog, a feed bar for the feed dog riding on the peripheral surface of the cam element and having a member entered in the cam for imparting a positive vertical reciprocating movement to the feed dog, and a rocker arm actuated by the feed shaft, imparting positive lateral reciprocation to the feed dog.

8. A sewing machine comprising co-axial feed and looper shafts, a cam element rotatable with the looper shaft having a cam in one of its side faces, the peripheral surface of said cam element corresponding with the cam, 25 a feed dog riding on the peripheral surface of the cam element and having a member entered in the cam for imparting positive vertical reciprocating movement to the feed dog and a rocker arm actuated by the feed 30 shaft, imparting positive lateral reciprocation to the feed dog, said rocker arm having a slot radial to the center of the feed shaft to receive said member and provide for its vertical reciprocation.

Toronto, January 25th, 1919.
